UNITED STATES PATENT OFFICE.

ALEXANDER T. BROWN, OF SYRACUSE, NEW YORK.

TYPE-WRITING MACHINE.

SPECIFICATION forming part of Letters Patent No. 411,421, dated September 24, 1889.

Application filed October 31, 1887. Serial No. 253,893. (No model.)

To all whom it may concern:

Be it known that I, ALEXANDER T. BROWN, residing at Syracuse, in the county of Onondaga and State of New York, have invented 5 certain new and useful Improvements in Type-Writing Machines, of which the following is a specification, reference being had therein to the accompanying drawings.

This invention relates to type-writing machines; and it consists in a brush or cleaning attachment for such machines by which all 10 the printing characters can be readily cleaned.

The object of the invention is to produce 15 an attachment by which the printing characters of a type-writing machine may be cleaned simultaneously.

Figure 1 represents so much of a well-known class of type-writing machines as is necessary to an understanding of this invention, the machine being shown partly in section and partly in end elevation with the type-cleaning attachment in position. Fig. 2 is a side elevation of a cleaner, its supporting-bracket, and operating-handle, the latter 25 partly broken away. Fig. 3 is a top plan of rotary cleaner or brush detached. Fig. 4 is a vertical section of same.

In the well-known "Remington," "Caligraph," and other type-writing machines of 30 similar character the printing types or characters are placed on the end of levers and are usually in a circle. When in depressed position, the printing characters face inward, and surround a circle, or nearly so. By applying and rotating 35 a circular brush of proper size to the face of these characters all may be cleaned at once. Of course many modifications of this idea may be easily devised. If the characters are not quite in a circle, the resilience of 40 the brush will still make it effective. The brush may be oscillated instead of rotated, and this will in effect be a reciprocation of the brush and the equivalent in effect of a right-line movement of a straight brush in contact 45 with the printing characters. It is apparent, also, that the cleaner may be any usual cleaner for the purpose.

I have shown the brush illustrated as a suitable one, and will now describe one form of 50 mechanism for carrying the invention into operation.

In the device illustrated, A indicates the frame of the machine.

B are upright standards supporting the ring C, to which the type-levers D are pivoted. 55 On these levers the printing characters E are mounted.

All the devices for operating the printing characters are usual and well-known in type-writers, and form no part of the present invention. 60 Only a few of the type-levers are shown.

To the frame A, I attach a bracket F by screws or in other convenient manner. The end of this bracket has a screw-threaded 65 socket G below the center of the circle formed by the printing characters when in depressed position, as shown in Fig. 1. An annular brush or cleaner H is connected by a spider I with a screw-shaft K, which shaft enters and 70 fits the thread of socket G. The shaft K terminates at its upper end in the key-post L, and a key M, provided with a crank N, may be applied to this post when desired, thus forming a shifter for the brush or cleaner. 75 The screw-shaft K enters the socket G so far that the brush or cleaner H may be run down to the position shown in Fig. 1 below or out of the way of the printing characters. By applying the key M, as in Fig. 1, and turning 80 the crank N the cleaner G may be raised and at the same time rotated until the brush operates on all the printing characters. A few quick turns in both directions will serve to pass the brush in reverse or spiral direction 85 past and in contact with the face of all the printing characters, effectually removing dust and surplus ink and leaving the type or printing characters in good condition for printing.

When not in use, the brush may remain 90 below the levers or may be removed from the machine entirely.

It will be understood that while in compliance with the law I have described the best form of mechanism with which I am now acquainted, I do not limit myself to the precise 95 details of construction shown and described.

I do not herein claim the form of lever on which the printing characters are mounted, as the same will be claimed in a later application.

What I claim is—

1. The combination, with the printing characters of a type-writing machine, of a type-cleaner in proximity to a plurality of said printing characters, and a brush-shifter by which the cleaner may be moved in contact with and clean a number of the characters simultaneously, substantially as described.
2. The combination, with the printing characters of a type-writing machine arranged in a circle, of a circular brush of about the same radius supported on the machine in proximity to said characters, so that the brush can come in contact with a plurality of type at one time, substantially as described.
3. The combination, with the printing characters of a type-writing machine, of a brush supported on the machine, a shifter for moving said brush laterally, and mechanism (as a screw and nut) for shifting the brush vertically with reference to the printing characters, substantially as described.
4. The combination, with the printing characters of a type-writing machine arranged in a circle, of a circular cleaner and a screw-threaded shaft attached to said cleaner and operating in a socket in alignment with the center of the circle round which the printing characters are arranged.
5. The combination, with the printing characters of a type-writing machine arranged in a circle, of a rotating brush supported in a socket beneath the center of said circle, and a detachable handle by which said brush may be operated, substantially as described.

In testimony whereof I affix my signature 35
in presence of two witnesses.

ALEX. T. BROWN.
